UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

AUTOMATICALLY CONTROLLED RADIOPHONIC RECEIVER

Application filed June 27, 1939. Serial No. 374,801.

My present invention relates to automatically controlled receivers, and, more particularly, to a novel means for automatically controlling the tuning and volume of a radio 5 receiver.

Automatically controlled radio receivers, especially of the push-button type, are well-known. These prior devices, however, are unnecessarily complicated in their mechanical structure. For example, they often involve delicate mechanical adjustments, easily subject to abuse during operation of the set. Again, the control of output volume in prior automatic devices is independent of the tuning mechanism; or, if automatic volume control is employed, expensively combined with the tuning device. These disadvantages, coupled with the fact that an inexpensive, automatic receiver is much more desirable than 15 a highly complex and costly mechanism, make it necessary to improve prior automatic radio receivers.

Now, I have designed a receiver which will incorporate the desirable features of prior 25 devices, and at the same time, retain the advantages of economy and simplicity of operation. Briefly, the novel automatic radio receiver, herein disclosed, embodies means so arranged that whatever station is selected, a 30 volume control adjustment is simultaneously selected, the latter control having been adjusted for a predetermined volume upon installation of the receiver.

Thus, the present invention has for its main 35 object the provision of an automatically controlled radio receiver having predetermined volume control combined with predetermined tuning, both control and tuning being effected by the utilization of a simple selective switch- 40 ing means.

Another important object of the present invention is to provide a radio receiving set embodying a plurality of circuits, each of said circuits being fixedly tuned to a predetermined station, a plurality of selective switches connected to said circuits, each of said switches being connected with a predetermined one of said circuits, said switches being so constructed that it is merely necessary to simultaneously connect the terminals

of the wires of a given circuit to obtain the station to which the circuit is tuned.

Another object of the invention is to provide a push-button type of radio receiver embodying station selector switches so designed 55 that when a given switch is not in use the tuned circuit terminal contacts arranged in the said switch are electro-statically shielded from each other, and novel key means for connecting the contacts to select a given station. 60

Other objects of the invention are to improve generally the simplicity and efficiency of automatically controlled radio receivers, and to provide a push-button type of receiver 65 which is durable, simple, reliable in operation, and economical to manufacture.

The novel features which I believe to be characteristic of my invention are set forth in particularity in the appended claims, the 70 invention itself, however, as to both its organization and method of operation will best be understood by reference to the following description taken in connection with the drawing in which I have indicated diagrammatically one circuit organization whereby my invention may be carried into effect. 75

In the drawing,

Fig. 1 shows diagrammatically a receiver 80 circuit embodying the invention,

Fig. 2 is a detail view of a modified form of station selector.

Referring to the accompanying drawing, in which like characters of reference indicate the same parts in the different views, there is 85 shown in Fig. 1, a grounded antenna circuit A, G, coupled, as at M₁, to the tuned input circuit of the first radio frequency tube 1. The tube 1 has been shown as a screen-grid type of electron emission device, it being understood, however, that the usual triode may 90 be employed.

The filament of tube 1 is energized from a source "A", the latter having its negative terminal grounded, there being a fixed resistance r₁ and variable resistor V in series in the lead from the positive terminal of the source to the positive leg of the filament. The negative leg of the filament is connected to a terminal contact P₂ through a variable resistor R₁, and 100

to a second terminal contact P_7 through a resistor R_2 . At a point distant from contact P_2 , along the periphery of insulation ring S , is disposed a grounded contact 5 P_5 . A grounded contact P_{10} is similarly disposed in insulation ring S_1 , at a point distant from contact P_7 .

In the input circuit of tube 1 are connected 10 a plurality of fixed condensers. For simplicity of showing, only two such elements C_1 and C_2 are shown. The fixed condenser C_1 is connected between the grid end of the coupling secondary and a contact P_1 disposed in ring S , the contact being spaced from the contacts P_2 and P_5 , as shown. The filament end 15 of the coupling secondary is grounded. It is to be noted that the fixed capacity C_1 is removably connected to the input circuit of tube 1, the points 4 denoting the means for maintaining the capacity in place.

The capacity may be of the well-known cartridge type, that is to say, mounted within 20 a protective cartridge casing provided with terminals at each end for easy replacement in the circuit. The capacity C_1 is so designed that it combines with the secondary of coupling M_1 to provide a circuit tuned to a predetermined frequency.

A second fixed capacity C_2 , also of the 25 replaceable, cartridge type, is connected in the input circuit of tube 1 in a manner analogous to the connection of fixed capacity C_1 , one end of the capacity being connected between the coupling secondary and grid of tube 1 and the other end to a contact P_6 . This contact P_6 is disposed in the periphery of insulation ring S_1 , and is spaced, as shown, from contacts P_7 and P_{10} . It is to be understood that the capacity C_2 is so designed that it combines with 30 the inductance of the secondary of coupling M_1 to provide a tuning circuit which has a frequency different from the frequency provided by the circuit in which the capacity C_1 is disposed.

The plate circuit of tube 1 is energized from 35 a source having a potential of 90 volts, there being an inductance L connected between the plate circuit and the positive terminal of the source, the capacity C_6 , grounded at one terminal, being connected at its opposite end to the positive terminal of the plate source.

The second stage of the tuned radio frequency includes the triode 2, which has its 40 input circuit tuned by means of the inductance L , the replaceable, fixed capacity C_3 , and the replaceable fixed capacity C_4 . These latter capacities are preferably both of the cartridge type and are removably maintained in position by means denoted as 4', it being understood that these capacities may be interchanged with the capacities C_1 , C_2 .

The capacity C_3 is connected between the 45 grid circuit of tube 2 and the contact P_4 , it being observed that the latter is disposed in the ring S and spaced from the remaining

contacts. The fixed capacity C_4 is likewise connected between the grid circuit of the tube 2 and a contact P_8 , the latter being disposed in the ring S_1 , and spaced from the other contacts in the said ring.

The tube 2 is rendered asymmetric in operation by the provision of a capacity C_5 in the grid circuit thereof, and a grid leak r_3 between its grid and filament. The filament of tube 2 is energized from the source "A", 50 it being noted that this source also energizes the filament of tube 1, the negative leg of the filament of tube 2 being connected to a contact P_4 in the ring S and contact P_9 in the ring S_1 . Each of these contacts are spaced from the contacts adjoining them, as shown clearly in Fig. 1. The positive leg of the filament of tube 2 is connected to the positive terminal of source "A" through a resistor r_2 .

It is to be pointed out that the capacity C_3 is so designed that it combines with the inductance L to provide a circuit tuned to the same frequency to which the circuit including the capacity C_1 , is tuned. In the same manner the capacity C_4 combines with the inductance L to provide a circuit tuned to the same frequency to which the circuit including the capacity C_2 is tuned.

The plate circuit of tube 2 is energized from a 45 volt source, the said plate circuit being coupled to the input circuit of the first audio tube 3 through an audio frequency coupling M_2 . The grid of the audio tube 3 is biased by means of a source "C", the positive terminal of the latter being connected between the negative legs of the filaments of tubes 2 and 3.

It will be observed that the filament of tube 3 is connected in parallel with the filament of tube 2, and is energized from the same source "A". The plate of tube 3 is energized from a 90 volt source, the amplified output of the audio tube 3 being utilized in any well-known manner, as by phones, loud-speaker, etc.

I have designated the ring S , for the purpose of illustration, as WJZ, and the ring S_1 as WEAF, it being understood that these designations represent the station call letters of the tuned circuits which are connected to each of the rings. These rings and their respective contacts will hereinafter be called station selector switches, it being understood that it is merely necessary to insert a metallic key means in a ring in order to connect the various contacts disposed in a given ring to an operative receiving circuit. It is obvious, of course, that each of the contacts are made of metal.

Thus, a metal key inserted in hole WJZ connects all five terminals P_1 , P_2 , P_3 , P_4 and P_5 , together. This connects condensers C_1 and C_2 to the two tuned circuits, completes the filament circuits of the detector and audio tubes through the fixed resistance r_2 , and also,

closes the filament circuit of the screen grid tube 1 through fixed resistance r_1 , volume reducing resistance V and volume equalizing resistance R_1 .

5 Placing a metal key or plug into aperture WEAF does the same, except that condensers C_2 and C_4 are connected in circuit so as to tune the receiver to WEAF instead of WJZ, R_2 being substituted for R_1 , it being understood that the key has been removed from the switch WJZ. The resistor r_1 is so designed that it just permits rated current to flow in the filament when no other resistance is in the circuit. The resistor R_1 is adjusted so that 15 with the variable resistance V equal to zero, the volume received from WJZ is a desirable amount under the existing conditions (the particular antenna, location, time of day, etc.).

20 Then, the resistance R_2 is similarly adjusted to give a desired volume for WEAF, preferably equal to that from WJZ. Should less volume be desired on either station, variable resistance V is cut into circuit by 25 means of a rheostat on the operating panel (not shown). It will be obvious that it will be necessary to have as many station selector switches as cartridge capacities in the input circuits of tubes 1 and 2. These cartridge 30 capacities are very inexpensive, and it will therefore be quite economical to vary the number of stations desired to be selected from the broadcasting band. If the metal key or plug is removable it will be seen that 35 the receiver is tamper-proof, inasmuch as only one possessing the key will be able to connect the contacts in a given switch.

However, in Fig. 2, I have shown a type 40 of selector switch in which a key 10 is permanently positioned in each of the selector switches, the particular insulation ring being designated, in Fig. 2 as S_2 . Six contacts are shown in this switch, assuming that three fixed capacities are used in the input 45 circuit of the first radio stage. The contacts are electro-statically shielded from one another, when a particular selector switch is not in use. It will be further observed that the lead wires to each contact may be protected by grounded shields shown in Fig. 2, as dotted lines. Each key 10 is so designed that by moving it in the direction of the arrow all contacts are simultaneously connected to one another, while moving the key in 50 the opposite direction simultaneously disconnects all contacts.

While I have indicated and described one system for carrying my invention into effect, it will be apparent to one skilled in the art 55 that my invention is by no means limited to the particular organization shown and described, but that many modifications in the circuit arrangements, as well as in the apparatus employed, may be made without de-

parting from the scope of my invention as set forth in the appended claims.

What I claim is:—

1. In combination, in a radio receiver, a plurality of radio frequency amplifier circuits, a frequency determining element in each circuit, an amplification control element, a source of energizing potential, a plurality of switches, each including a plurality of insulated contacts, one contact in each switch being grounded, the remaining contacts in each switch being connected to a predetermined frequency element, the amplification control element and potential source, and a conductive key for electrically connecting all the contacts in a given switch. 70

2. In combination, in a radio receiver, a plurality of radio frequency amplifier circuits, a frequency determining element in each circuit, an amplification control element, a source of energizing potential, a plurality of switches, each including a plurality of insulated contacts, one contact in each switch being grounded, the remaining contacts in each switch being connected to a predetermined frequency element, the amplification control element and potential source, a conductive key for electrically connecting all the contacts in a given switch, and means 80 for electrostatically shielding each contact in each switch. 90

3. A radio receiver comprising in combination, a radio frequency amplifier stage provided with a tuned input circuit, a detector stage, at least one tuned circuit disposed 100 between the amplifier and the detector input, at least one stage of audio frequency amplification following the detector, a source of energizing current connected to the cathodes of the tubes of said stages, each of said tuned 105 circuits including at least two frequency determining elements, at least two independent station selector switches each comprising a plurality of spaced insulated contacts, elements in said tuned circuits which resonate 110 their circuits to the same frequency being connected to a pair of contacts of the switch corresponding to said same frequency, one contact of each switch being maintained at the same potential as the low potential end 115 of said source, other contacts of each switch being connected to the high potential end of said source through said cathodes in each stage, and conductive means for electrically connecting together the contacts of a desired switch. 120

4. A radio receiver comprising in combination, a radio frequency amplifier stage provided with a tuned input circuit, a detector stage, at least one tuned circuit disposed 125 between the amplifier and the detector input, at least one stage of audio frequency amplification following the detector, a source of energizing current connected to the cathodes of the tubes of said stages, each of said 129

- tuned circuits including at least two frequency determining elements, at least two independent station selector switches each comprising a plurality of spaced insulated contacts, elements in said tuned circuits which resonate their circuits to the same frequency being connected to a pair of contacts of the switch corresponding to said same frequency, one contact of each switch being maintained at the same potential as the low potential end of said source, other contacts of each switch being connected to the high potential end of said source through said cathodes in each stage, conductive means for electrically connecting together the contacts of a desired switch and an amplification control means connected between the cathode of said amplifier and a contact of each of said switches.
5. A radio receiver comprising in combination, a radio frequency amplifier stage provided with a tuned input circuit, a detector stage, at least one tuned circuit disposed between the amplifier and the detector input, at least one stage of audio frequency amplification following the detector, a source of energizing current connected to the cathodes of the tubes of said stages, each of said tuned circuits including at least two frequency determining elements, at least two independent station selector switches each comprising a plurality of spaced insulated contacts, elements in said tuned circuits which resonate their circuits to the same frequency being connected to a pair of contacts of the switch corresponding to said same frequency, one contact of each switch being maintained at the same potential as the low potential end of said source, other contacts of each switch being connected to the high potential end of said source through said cathodes in each stage, and conductive means for electrically connecting together the contacts of a desired switch, each of said elements comprising a fixed condenser.
7. A radio receiver comprising in combination, a radio frequency amplifier stage provided with a tuned input circuit, a detector stage, at least one tuned circuit disposed between the amplifier and the detector input, at least one stage of audio frequency amplification following the detector, a source of energizing current connected to the cathodes of the tubes of said stages, each of said tuned circuits including at least two frequency determining elements, at least two independent station selector switches each comprising a plurality of spaced insulated contacts, elements in said tuned circuits which resonate their circuits to the same frequency being connected to a pair of contacts of the switch corresponding to said same frequency, one contact of each switch being maintained at the same potential as the low potential end of said source, other contacts of each switch being connected to the high potential end of said source through said cathodes in each stage, conductive means for electrically connecting together the contacts of a desired switch and means for electrostatically shielding the contacts of each switch from one another.
